[57] CLAIM

The ornamental design for a tens electrode, as shown and described.

DESCRIPTION

FIG. 1 is a front perspective view of a tens electrode showing my new design;

FIG. 2 is a top plan view thereof;

FIG. 3 is a left side elevational view thereof;

FIG. 4 is a rear elevational view thereof;

FIG. 5 is a right side elevational view thereof;

FIG. 6 is a front elevational view thereof;

FIG. 7 is a bottom plan view thereof;

FIG. 8 is a front perspective view of a tens electrode showing a second embodiment of my new design;

FIG. 9 is a front elevational view thereof;

FIG. 10 is a left side elevational view thereof;

FIG. 11 is a rear elevational view thereof;

FIG. 12 is a right side elevational view thereof;

FIG. 13 is a front elevational view thereof; and,

FIG. 14 is a bottom plan view thereof.

FIG. 4

FIG. 3

FIG. 2

FIG. 5

FIG. 6

FIG. 8**FIG. 14**

FIG. 11

FIG. 10

FIG. 9

FIG. 12

FIG. 13
